ATTORNEY

UNITED STATES PATENT OFFICE

123,720

DESIGN FOR A NEGLIGEE OR SIMILAR ARTICLE

Roslyn I. Appel, New York, N. Y.

Application October 2, 1940, Serial No. 95,563

Term of patent 3½ years

To all whom it may concern:

Be it known that I, Roslyn I. Appel, a citizen of the United States of America, residing in New York city, in the Borough of Manhattan, county and State of New York, have invented a new, original, and ornamental Design for a Neglige or Similar Article, of which the following is a specification, reference being had to the accompanying drawing, forming part thereof, wherein,

I claim:

The ornamental design for a neglige or similar article, substantially as shown.

ROSLYN I. APPEL.
